UNITED STATES PATENT OFFICE.

MICHAEL EVELEV, OF LEBANON, PENNSYLVANIA.

SHOE-POLISHING MACHINE.

Application filed March 28, 1922. Serial No. 547,428.

This invention relates to a shoe polishing machine, and the object is to provide a device of the type indicated which shall include a horizontally reciprocable member 5 driven by a motor, or in any other suitable manner, and carrying means for engaging brush mounting devices designed to be oscillated as upon a vertical axis and about a stationary shoe support.

10 A further object is to provide a particular form of brush assembly, the brushes per se having a configuration adapted for the oscillating movement specified.

15 A still further object is to provide particular means for distributing the polish.

20 A further object is to provide, in connection with the horizontal reciprocable element carrying rack bars, or the like, a series of brackets and mounting devices therefor, arranged in pairs, and including segmental toothed elements cooperating with the racks.

25 A still further object is to provide, in the construction specified, means whereby the segmental members are movable into position for engaging the racks by the pressure of the shoe on a pedal, when the foot is placed in proper position with reference to the brush.

30 With the foregoing and other objects in view, the invention consists in the novel construction and arrangement of elements described and claimed, it being understood that modifications may be made within the scope of the claims without departing from the spirit of the invention.

35 In the drawings, Figure 1 is a plan view of the machine; Figure 2 is a side elevation of the brush assembly, parts being in section; Figure 3 is a detail view, in plan, 40 with the brush back broken away, and showing structure described below; Figure 4 is a plan view of the plate on which the shoe rests and thru which the lever and pedal of Figure 2 project; Figure 5 is a plan view 45 of the lever having a pedal at one end and a segment at the other end adapted to engage and lift the segmental rack into operative engagement with one of the straight racks of Figure 1; Figures 6 and 7 are detail views 50 of a stirrup shown in the lower left corner of Figure 2.

55 In carrying out my invention, I employ a reciprocable element 1, driven in any suitable manner, as through the medium of a crank shaft 2 and an electric motor 3, with

the usual connections employed in such construction.

Element 1 is provided with racks 4 having the usual teeth designed for engaging and oscillating the brush mounting devices. 60 Rollers carried by the mounting devices referred to cooperate with the elements 5 adjacent to the racks 4, and facilitate the proper meshing of the engaging members. In practice, these rollers will be spaced to 65 engage the under sides of elements 5 when the segmental racks have been swung from the position of Figure 1 by the longitudinal movement of the straight racks. The rollers are designated 25'.

70 On both sides of element 1, I mount any suitable number of brushes in pairs, some being wet brushes for applying liquid polish, and the remaining brushes being dry and intended for polishing the shoes by applying friction.

75 Each brush assembly comprises a base plate 10 to be secured to the floor, and formed as shown, that is including a central portion and a segmental portion. Vertical 80 threaded posts 12 provide means for mounting a plate 13 secured by screws passing through apertures 15 into posts 12. Plate 13 is further provided with an opening 16 having connected therewith a slot 17.

85 An operating and controlling lever 18 is formed with a central downwardly deflected portion 19 and with a pedal 20 having a high portion and a low portion for cooperation with the heel of a man's shoe or a woman's 90 shoe, recessed portion 21 being intended for the latter. The pedal projects through the opening 16, the lever cooperating with the slot 17.

95 The lever 18 is formed with a segmental portion 23 acting as a bearing member for segmental rack 24 cooperating with the racks 4 of slidable member 1. Rollers 25' on the segmental rack cooperate with elements 5 above referred, and facilitate the meshing of 100 the racks when, upon depressing the rear end of lever 18, the forward portion is thrown upwardly, in order to place the brush in operation by imparting an oscillating movement to the brush assembly. The 105 shoe is stationary with reference to the plate 13 and lever 18 with its heel portion 20, and the segmental rack 24 is slidable on segment 23 forming a part of the lever.

110 A pin 27 is mounted on base plate 10 and

- is surrounded by a coil spring 28, and a washer 29 is located as shown. This heel portion moves upwardly when no pressure is applied to the latter, and the lever moving on portion 19 as a fulcrum is thrown to the dotted line position of Figure 2, that is the segmental racks drop to inoperative position. The forward tension springs 31 aid in this movement to inoperative position.
- 10 An unusual form of brush is employed, designed to take the place of several separate brushes for various parts of the shoe. This brush designated 33 is formed with a flexible back or outer portion, and is mounted as shown with reference to segmental rack 24 and is movable therewith. The brush practically envelops the shoe but is open at the rear, and the oscillating movement due to the cooperation of the rack members imparts a combination of movements to the brush, that is practically a horizontal movement across the toe portion and a movement in an approximately vertical direction at the sides of the upper and the rear portion thereof.
- 15 20 A stirrup 36 is secured to the rear of the brush as shown and is provided with a central portion 36' which encircles the pin 27 and provides for partial rotary movement incident to the oscillation of the brush assembly as a whole. Spring 28 gives the brush flexibility in a vertical direction.
- The wet brushes, or polish distributing brushes are similar in construction, thus far, and each is provided with an upper extension 37 hinged as at 38 and held by securing devices 39, an extension being employed when high shoes are being operated upon. Both the wet and dry brushes carry extensions.
- 25 30 35 40 The wet brushes are provided with cups or polish containers 40 connected by tubes 41 with the main portions of the brushes, and the upper extensions are provided with containers 42 connected by tubes 43 with the brushes 44 of the extensions. It will be observed that when the extensions are tilted as shown the outlets of the receptacles are higher than the receptacles themselves so that no polish is allowed to flow from the container 42. It is obvious that sufficient polish can be placed in receptacles 40, 42 by an attendant, for one operation. The blacking carried to various points by the tubes is distributed more thoroughly over the surface of the shoes by the action of the brushes.
- 45 50 55 60 65 From the foregoing it will be understood that any two of the brushes may be employed by a given individual, the polish supplied thereto being black or tan in accordance with the individual requirement, some of the brushes using one color and some of the brushes using the other. Various colors or shades may be provided if desired. Only those brushes required at the given time will

actually be in operation, since no motion is imparted to the brush carrying devices unless pressure is applied to the pedal 20.

Having thus described my invention I claim:

1. In a shoe polishing machine, a reciprocable element, engaging means thereon, and brush holding devices cooperating with the engaging means and movable, about pivotal points in the plane of movement of the reciprocable element, and on the opposite sides thereof.

2. In a shoe polishing machine, a reciprocable element, engaging means thereon, brush holding means normally inactive, and partly rotatable in an approximately horizontal direction by the engaging means on the reciprocable element, and foot-pressure operated means for moving the brush holding means vertically into operative relation with the engaging means.

3. In a shoe polishing machine, a horizontally reciprocable element, brush holding devices including segmental rack members cooperating with oppositely located parallel sides of said reciprocable element and each oscillated thereby in an arc-shaped path, and in the plane of movement of the reciprocable element.

4. In a shoe polishing machine, brush holding devices arranged in parallel rows, a brush carried by each of said devices, means for pivotally mounting the brush holding means for oscillation in an arc struck from the pivotal point, and means movable longitudinally between said brush holding devices for imparting such oscillating movement.

5. In a shoe polishing machine, brush holding means, a brush carried thereby, means for pivotally mounting the brush holding means for oscillation in an arc struck from the pivotal point, means including a segmental rack and a rack member reciprocable in a straight path for imparting such oscillating movement, the pivotal mounting means being spaced outwardly from the path of travel of the reciprocable rack, and a pedal for throwing the brush holding means into operative position.

6. In a shoe polishing machine, brush holding means, means for retaining said brush holding means normally inactive, a pedal for throwing said holding means to operative position, and a reciprocable element engaging the holding means when in operative position and imparting movement thereto about an axis perpendicular to the plane of movement of the reciprocable element.

7. In a shoe polishing machine, a brush assembly comprising a base, a lever mounted for movement in a vertical plane above the base, a pedal carried by the lever, a segmental engaging device elevated by the tilt-

- ing of the lever upon pressure exerted on the pedal, and positioned for engagement by a driving member, and a brush movable with the segmental engaging device.
- 5 8. In a shoe polishing machine, a driving member, a brush assembly comprising a base, a plate mounted above the base and spaced therefrom, a lever between the base and the plate and adapted to project through the plate, a segmental member carried by the lever, a segmental rack movable over the segmental member and positioned for engagement by said driving member when the lever is depressed, and a brush 10 movable with the rack.
9. In a shoe polishing machine, brush mounting means, a resiliently held brush carried thereby and comprising a member extending across the toe portion of a shoe 15 and in a vertical direction along the sides of the upper, and means for distributing polish to the brush, a portion of said brush being movable to throw an element of the polish distributing means to inoperative position.
- 20 10. In a shoe polishing machine, brush mounting means, a resiliently held brush carried thereby and comprising a member extending across the toe portion of a shoe and in a vertical direction along the sides 25 of the upper, and a hinged extension brush 30

connected with the brush first named and enveloping the upper portion of a high shoe.

11. In a shoe polishing machine, brush mounting means, a resiliently held brush carried thereby and comprising a member 35 extending across the toe portion of a shoe and in a vertical direction along the sides of the upper, and a hinged extension brush connected with the brush first named and enveloping the upper portion of a high shoe, 40 and means for distributing polish to the extension brush.

12. In a shoe polishing machine, a driving member, a brush assembly comprising a base, a foot rest spaced above the base, a 45 tiltable lever below the foot rest and partly projecting through said foot rest, a brush adapted to extend around a shoe upper, a device connected with the brush and imparting movement thereto, said device being 50 slidably mounted on one end of the lever and operated by the driving member, a stirrup having spaced upper ends connected with the sides of the brush, the lever passing through the stirrup, and a spring interposed 55 between the middle portion of the stirrup and the under side of the lever.

In testimony whereof I affix my signature.

MICHAEL EVELEV.
